UNITED STATES PATENT OFFICE.

WINFIELD P. CARTER, OF RAYMOND, ILLINOIS.

GRAIN-DOOR FOR RAILROAD-CARS.

No. 861,500.

Specification of Letters Patent.

Patented July 30, 1907.

Application filed July 3, 1905. Serial No. 268,161.

To all whom it may concern:

Be it known that I, WINFIELD P. CARTER, a citizen of the United States, residing at Raymond, in the county of Montgomery and State of Illinois, have invented a new and useful Grain-Door for Railroad-Cars, of which the following is a specification.

This invention relates to grain doors for railroad cars and it has for its objects to simplify and improve the construction and operation of this class of devices.

10 With these and other ends in view, which will readily appear as the nature of the invention is better understood, the same consists in the improved construction and novel arrangement and combination of parts, which will be hereinafter fully described and

15 particularly pointed out in the claims.

In the accompanying drawings has been illustrated a simple and preferred form of the invention. In said drawings, Figure 1 is an interior elevation showing a portion of the side wall of a car equipped with the 20 invention. Fig. 2 is a similar view showing the grain door suspended adjacent to one side of the door opening. Fig. 3 is a vertical sectional view taken on the plane indicated by the line 3—3 in Fig. 1. Fig. 4 is a perspective detail view of one of the grain door 25 hangers. Fig. 5 is a perspective detail view of one of the keepers connecting the door with the hangers. Fig. 6 is a perspective detail view of the gravity latch used for securing the grain door in inoperative position. Fig. 7 is a detail view illustrating one of the 30 hooks for securing the grain door in its closed or operative position.

Corresponding parts in the several figures are indicated throughout by similar characters of reference.

The present invention is applicable to any ordinary 35 railroad freight car, of which, in the drawings, 1, designates one of the sills, 2, one of the sides, 3, the door opening, and 4, 4 the posts or uprights adjacent to said door opening. 5 is a section of the floor. Upon the inner side of the side wall of the car, above the door opening and extending to one side of the latter, is supported a track rail consisting of a bar, 6, the same being 40 preferably rectangular in cross section, and supported at a distance from the wall, as upon brackets 6', and said track rail being of a length somewhat exceeding twice the width of the door opening. Supported 45 slidably upon said track rail are hangers 7, 7 which consist of flat metallic strips having rectangular slots, as 8, engaging the track rail and provided in their outer edges, near their upper ends, with downwardly 50 inclined recesses 9 below which are formed outstanding lips or hook members 10 the points of which extend beyond the edges of the strips, as will be seen in Figs. 3 and 4, while the inner ends of the recesses 9 are located in the bodies of the strips; this construction being resorted to in order to avoid the pos-

sibility of the parts being bent, contorted, or twisted out of shape, as is liable to be the case when the hangers are constructed of rods or wires bent to form supporting hooks. The lower ends of the hangers are outturned to form supporting lugs or shoulders 11. 60

It will be seen that, under the construction herein described, the hangers 7 are composed of flat strips or straps of sheet metal, adapted to lie compactly in contact with the side edges of the grain door when the latter is raised or elevated; hangers of this character 65 are found much preferable to hangers composed of rods or wires which have to be spaced from the door supported thereby.

The grain door 12, which may be of any desired construction, is provided at its upper corners with keepers 70 13 slidably engaging the hangers, and holding said hangers constantly in contact with the side edges of the grain door, said keepers being provided in their front sides with notches 14 extending upwardly from their lower edges and in their rear sides with similar 75 notches 15 extending downwardly from their upper edges. The grain door may be of any desired height and the hangers are so proportioned with relation to the door that when the lower edge of the latter rests upon the floor of the car, the ends of the keepers shall simultaneously rest and be supported upon the lugs or shoulders 11 at the free lower ends of the hangers, so that said hangers and keepers shall at no time be exposed to excessive or injurious strain. It will also be 80 seen that owing to the construction of the keepers with 85 the notches 14 and 15, the door will have some freedom of movement with relation to the hangers, so that, when the door is lifted to the raised position indicated in Fig. 2 of the drawings, the keepers will readily pass into engagement with the recesses 9 in the hangers and 90 be suspended or supported upon the latter, the front parts of the keepers being readily guided over the beveled or outstanding lips 10 into said recesses. In like manner disengagement of the keepers from the recesses 9 may be readily effected for the purpose of lowering the door by first slightly lifting the latter to disengage the keepers from the recesses, and then tilting the upper edge of the door to permit the front parts of the keepers to pass over the lips 10, thus permitting 95 the door to be lowered. 100

Pivotedly mounted upon the inner side of the car wall, above the rail 6 and in approximate alinement with the side of the door opening, beyond which the track rail is extended, is a gravity latch 16 which is beveled upon its under side so as to permit the hanger 105 7 which moves past the door opening to slide under it to the position seen in Fig. 2 of the drawings, by reference to which it will be understood that the door will thus be locked or secured in an open or inoperative position, said door being meanwhile supported by means of 110

the keepers 13 in the recesses 9 of the hangers. To restore the door to a position in alinement with the opening, the gravity latch 16 must be operated by hand to permit the hanger to slide under it.

- 5   Guides 17, 18 are secured adjacent to the door opening 3, at opposite sides of the latter; the guide 17 being of a height approximately equal to that of the door, while the guide 18 is only of such a height as to permit the door to move over its upper end; said guides are for 10 the purpose of retaining the grain door, when closed, in close contact with the inner side of the car wall so as to absolutely prevent leakage of grain. The door is provided upon its inner side with a handle 19 whereby it may be conveniently manipulated.
- 15   The keepers 13 at the upper corners of the door are provided in their outer walls with apertures 20 adapted to be engaged by hooks 21, which latter may be secured, as by means of staples 22, to the sides of the posts or uprights 4. By means of these hooks, the upper edges 20 of the grain doors may be drawn outward, so that the side edges of said doors shall be held in intimate contact with the inner sides of the walls.
- In the outer sides of the doors, near their lower edges, are embedded blocks 24 of metal, forming abutments 25 against which the point of a crow-bar may be rested for the purpose of prying the doors open, when necessary, without battering or otherwise injuring said doors.

From the foregoing description, taken in connection with the drawings hereto annexed, the operation and

advantages of this invention will be readily understood 30 by those skilled in the art to which it appertains. The construction of the improved grain door is simple and inexpensive; it may be readily applied to freight cars of ordinary construction; and it may, when thus applied, be readily moved to an out of the way position 35 where it does not in the least obstruct the use of the car for the transportation of ordinary freight. The parts used in the make up of the device are all of simple and inexpensive construction, and may be readily assembled for use in the manner indicated. 40

Having thus described the invention, what is claimed is:—

The combination with a grain car, of a track supported above the door opening, hangers swung on the track and having near their upper ends outstanding lips defining 45 downwardly-inclined seats, and at their lower ends oppositely-projecting lugs, a door, and reinforcing keepers secured to the upper corners of the door with one arm on each side thereof and through which the lower ends of the hangers project and with which the lugs engage, the keepers being provided with alined oppositely-disposed recesses 50 extending from the top and bottom of the opposite arms, respectively, to permit the door to tilt and allow the keepers to pass the lips and engage with the seats to hold the door raised.

In testimony that I claim the foregoing as my own, I have hereto affixed my signature in the presence of two witnesses.

WINFIELD P. CARTER.
